UNITED STATES PATENT OFFICE.

WILLIAM E. GINN, OF BALTIMORE, MARYLAND, ASSIGNOR OF TWO-THIRDS
TO WILLIAM K. ISAACS AND HARRY L. ISAACS, OF SAME PLACE.

TOOL-SHARPENER.

SPECIFICATION forming part of Letters Patent No. 502,459, dated August 1, 1893.

Application filed January 25, 1893. Serial No. 459,759. (No model.)

To all whom it may concern:

Be it known that I, WILLIAM E. GINN, a citizen of the United States, residing at Baltimore, in the State of Maryland, have invented 5
certain new and useful Improvements in Tool-
Sharpeners; and I do declare the following to
be a full, clear, and exact description of the
invention, such as will enable others skilled in
the art to which it appertains to make and use
10 the same, reference being had to the accom-
panying drawings, and to the letters of refer-
ence marked thereon, which form a part of this
specification.

This invention relates to improvements in
15 tool sharpeners, and is especially designed to
furnish a device by means of which scissors,
shears and other like cutting instruments
can be readily and conveniently sharpened.
These objects I attain by the means illus-
20 trated in the accompanying drawings, in
which—

Figure 1. represents a perspective view of
my improved device, showing the method of
using it. Fig. 2. represents a side elevation
25 of the device. Fig. 3. represents a transverse
vertical sectional view taken on the line $x-x$
of Fig. 2. Fig. 4. represents a detail sectional
view of a modification of my invention, and
Fig. 5. a perspective view of a portion of the
30 device, detached.

Referring to the drawings, the letter A indi-
cates a rectangular metallic frame con-
structed of preferably wire, grooved on the
inner sides as clearly shown in Fig. 1. of the
35 drawings.

The letter B indicates a frame or carriage,
which is provided at its lower corners with
laterally projecting brackets C, which over-
set the lower rail of the frame A, loosely, so
40 as to travel thereon. D indicates a boss pro-
jecting inwardly from said frame or carriage
B. The said boss is diametrically slotted as
indicated by the letter E, the slot being open
45 at the bottom and approximately of the shape,
of the member of a pair of scissors or other
tool to be sharpened.

The letter F indicates an annular frame of

a diameter, about equal to the width of the
frame A. It is provided with a peripheral
rim G which is preferably, conical in cross
section, and which travels in the grooves of
the frame A. Within said annular frame is
located a grinding annulus H which may be
made of natural stone, emery composites or
other abrasive material. The grinding annu-
lus is of such character and so arranged that
55 when in place, its inner face will rotate close
up to the periphery of the boss on the frame,
so as to bear against the tool to be sharpened,
and by rotating against it, produce a sharp
50 cutting edge.

The annular casing carrying the grinding
annulus is confined loosely in the carriage
by means of the lugs I, which over-set the an-
nular peripheral rim of the frame F, so as to
65 permit the said frame to freely rotate.

In the modification shown in Fig. 4. of the
drawings, the annular rim on the frame F' is
provided with cog teeth and the lower rail of
the frame A' is provided with similar teeth,
70 with which the teeth on the periphery of the
frame F' intermesh. The upper rail of the
frame in this modification is simply grooved
longitudinally so as to guide the frame F' and
at the same time permit the grinding annulus 75
to rotate, freely.

The operation of my invention will be read-
ily understood in connection with the above
description and is as follows:—One member
of the scissors, or the tool to be sharpened is
80 placed in the slot in the boss of the carriage
as shown in Fig. 1. of the drawings. The
frame A is held by the handle, by one hand
of the operator and the carriage, moved back
and forth by the other hand in which the 85
scissors or tool is held, as shown in said fig-
ure. The reciprocating movement given to
the carriage causes the annular disk to rotate
so as to abrade and sharpen the edge of the
90 tool. To properly sharpen the entire length
of the edge of the tool it is advanced from
time to time, through the slot in the boss of
the carriage.

Having thus described my invention and

the method of operating the same, what I claim, and desire to secure by Letters Patent, is—

The combination with the rectangular frame, of the carriage having lateral brackets over-setting one of the rails thereof, the annular frame arranged to rotate in said carriage and the grinding annulus, confined in said frame, substantially as specified.

In testimony whereof I affix my signature in the presence of two witnesses.

WILLIAM E. GINN.
